UNITED STATES PATENT OFFICE.

MORRIS MARTIN, OF MALDEN, MASSACHUSETTS, ASSIGNOR OF ONE-HALF
TO THOMAS J. DRUMMOND, OF BOSTON, MASSACHUSETTS.

PROJECTING APPARATUS.

SPECIFICATION forming part of Letters Patent No. 760,797, dated May 24, 1904.

Application filed January 31, 1898. Serial No. 668,546. (No model.)

To all whom it may concern:

Be it known that I, MORRIS MARTIN, of Malden, county of Middlesex, State of Massachusetts, have invented an Improvement in Projecting Apparatus, of which the following description, in connection with the accompanying drawings, is a specification, like letters on the drawings representing like parts.

This invention has for its object the production of a novel apparatus which I have chosen to designate by the name of "projecting apparatus," it being designed to display in light and shade words, either exhibiting said words singly or by indicating said words as an operation of spelling, each letter being exhibited in the proper order of spelling the word.

My projecting apparatus is provided with a pattern-surface, preferably in the form of a strip of flexible material, such as paper, having holes or slots, which may be of different lengths, arranged in the desired order to operate one after another or play upon suitable targets carrying characters—such as letters, words, numbers, figures, designs—or features which it is desired shall, by or through the action of rays of light, be thrown out or displayed through the medium of a strong light—such, for instance, as an electric or calcium light, an oil-lamp, or reflected or solar rays. The pattern-surface referred to may and will preferably be kept steadily in motion or be driven at desired speed by electric or other suitable motive power.

My invention consists in a projecting apparatus comprising a case having an opening, means for producing a strong light within the case, a series of targets carrying characters, and means for playing upon the targets for throwing the characters between the case-opening and the lighting means.

My invention consists, further, in a projecting apparatus of specific construction, as hereinafter described and claimed.

Figure 1 is a section of a projecting apparatus embodying my invention, said section being in the line α of Fig. 2. Fig. 2 is a side elevation of a projecting apparatus, partially broken out centrally and part in section to

show some of the interior construction, the 50 motor being omitted. Fig. 3 shows a target having a plain or darkening character. Fig. 4 shows a modified form of pattern-surface.

The outside casing of my projecting apparatus is herein shown as composed of a base 55 B and a top or cover part B', the top being represented as hinged at a to the base. The base contains in the embodiment of my invention herein shown a small electric motor C, the rotating shaft c of which is provided 60 with a friction-pulley or other driver, as c' , which acts on and rotates a suitable intermediate idler c'' , which engages a suitable pulley or driven member c''' , fast on, preferably, the cylinder c^4 , employed to support, as herein 65 shown, the flexible pattern-surface d , represented as a strip of paper having a series of holes or slots d' arranged in the proper predetermined order desired for the work to be done or the character to be displayed. Preferably 70 the cylinder c^4 , to which is fixed the wheel c^3 , is made to feed or move the pattern surface or strip. This electric motor may be readily driven by connecting the terminals $e e'$ of the motor-circuit with any suitable source of electric supply. Instead of the electric motor a motor actuated by spring or weight or manual power might be employed; but the electric motor would possess the great advantage 75 of continuous operation with the minimum of attention. The cylinder will preferably be mounted on a shaft the ends of which will turn on or in suitable center bearings, one of which is shown at c^5 in Fig. 2. The cylinder is provided with a series of annular unobstructed grooves, said grooves being equidistant and occupying positions in line with the holes in the pattern-surface, said holes falling 80 in longitudinal lines.

The flexible pattern-surface d is shown as 90 taken from a suitable delivery roll or shaft d' , having its ends supported in suitable bearings d'' , herein shown as arranged outside said base, the pattern-surface being led to and over said cylinder through a suitable space left between the base and top, said pattern-surface 95 preferably passing from the casing at its opposite side, and then it may drop or be wound,

if desired, on any usual take-up roll, such as commonly employed to wind telegraphic or register tape, and it is shown having at pre-selected places elongated openings d^x , (see 5 Fig. 2,) the peculiar function of which will hereinafter appear. If desired and the characters displayed are to be soon repeated, then the pattern-surface may be of the shape of an endless belt, as represented in Fig. 4, two 10 cylinders being employed to keep it in position. The length of exposure of any character may be determined by making the opening in the pattern-surface to control its exposure more or less long, or this peculiar 15 function may be obtained in many other ways. The paper may be kept down on the cylinder by any usual pressing device, as a roll d^4 , and said roll may have a yielding surface, so that it may exert sufficient pressure on the paper 20 to enable the paper to be fed by the movement of the cylinder. The roll d^4 will preferably have its bearings supported in the top, and instead of the particular roll shown I may employ any other suitable device for this 25 purpose. I have herein shown the top as provided at one end with a tube, having, it will be understood, a suitable lens L of any desired magnifying power—lenses such, for instance, as are used in stereopticons and magic-lanterns— 30 and at or near the opposite end of said top I have shown suitably suspended an incandescent electric lamp L' , I having chosen it as one form of well-known apparatus for producing or centering rays of light, and this lamp may 35 be connected in circuit with any known or suitable source of supply.

The apparatus is further provided with a series of targets f . These targets are herein shown as bent levers pivotally mounted on a 40 suitable rod f' , one arm of each of said levers carrying at its end a character, as f^2 , which will more or less obstruct the passage of the rays of light through the lens, thus enabling the light-rays leaving the lens to assume different 45 forms, that depending on the particular shape of the characters carried by the levers. Each of the other arms of these levers rides on the pattern-surface or paper. Being moved under it is a trip-arm, and, as herein shown, when a 50 hole d^x (see Fig. 2) of a series of such holes in said paper comes under a trip-arm the character carried by the other arm is put into the focus of the rays of light, and the rays of light passing from the lens will vary according to 55 the shape of the character then in operative position. For instance, the characters may be letters, (see A,) and in such case there will be twenty-six characters, one for each letter, and one of these characters—as, for instance, 60 the one located next the lens, (see f^3)—may be a full disk, so that when it comes into the focus of the rays there will be temporarily a cessation of light-rays shown, or it may be put into position, the end of a word being spelled out 65 by successively displaying said characters.

As herein shown, the characters overbalance the levers, so that the shorter ends of said levers ride on the paper; but movement of said levers by gravity is determined by a stop-rod g .

The projecting apparatus hereinbefore referred to is capable of being adapted to a great variety of work. I have herein specifically illustrated it as adapted to spell out words, the characters represented being letters; but it will be obvious to one skilled in the art that instead of the characters being single letters they may be two or more letters or a word, or they may be stenciled plates or disks representing different characters or designs more or less comical, or otherwise. 80

This apparatus may be used for advertising purposes, and the electric motor may be started and the electric light turned on, and the apparatus may be thereafter run without any attention, and the characters represented 85 on the targets may be displayed one after the other in the predetermined or desired order, that being absolutely controlled by or through the pattern-surface. This invention is not limited, however, to the exact kind of pattern-surface shown, and instead I may employ any other usual or suitable pattern-surface; but the employment of the flexible pattern-surface is of great advantage, because of its cheapness and because a pattern-surface 90 of one character may be readily put into position to take the place of a very different pattern-surface.

This invention, besides being used for advertising purposes, may be used on shipboard 100 to convey intelligence from one ship to another at a distance, or it may be used in a lighthouse to throw out into the atmosphere any desired number, word, or signal to indicate a particular lighthouse. 105

This apparatus may be used, if desired, after the telegraphic code, the character-targets being disks or operated to fully obstruct the light-rays for a longer or shorter period, the difference in exposure of the light-rays 110 corresponding with the dots and dashes of a Morse telegraph. So, also, if desired, the targets may be composed of glass of different colors, or the targets may contain any usual or suitable chemical substances adapted to 115 change or modify the color of light-rays, so that by a change of position of these targets any degree of color or intensity of color may be gained. It is unnecessary herein to show a target containing chemical substances for 120 modifying or changing the hues or color of light-rays passing through them, for such knowledge is had and in the possession of people skilled in the art appertaining thereto.

I have herein shown the apparatus as provided with a single tube containing a lens; but I desire it to be understood that the apparatus or case may contain any desired number of tubes and lenses, so that, if desired, I may display a plurality of different characters or 130

designs, making up, if need be, an entire word or a series of different colors or characters. So, also, by the use of a plurality of tubes the characters thrown out into the light may be 5 gradually made one to take the place of the other without any startling effect, or they may be handled as dissolving views.

I contemplate that by the use of this apparatus I may, with excessively strong and powerful light, throw out the characters upon a 10 cloud in the heavens.

I have herein shown the case as composed of a base and a top; but it will be understood that the case in itself forms no part of this 15 invention, and it may be of any usual or desired or suitable shape and of any usual or suitable material.

It will be understood that I may employ herein any usual form or character of lens 20 commonly employed to control light in any stereopticon, magic-lantern, &c.

For greater simplicity in the operation of the parts the cylinder ³ is made the feeding device for the pattern-surface; but it will be 25 obvious that this invention would not be departed from if some other means were applied to the strip to draw it over the surface of the cylinder and the said cylinder was not itself made the sole feeding device.

30 For the best results I prefer, in case the apparatus is used to spell out words, in the formation of letters that the letters of the character-targets nearer the lens be smaller than those nearer the source of light, this variation in size being more or less, according to the length of the apparatus and the number of characters to be displayed.

In case the apparatus is used for signaling from one ship to another such apparatus will 40 be rotated at a given or standard speed, so that the pattern-surface will move uniformly, and this uniformity of movement being understood the varying period of light may be noted and interpreted as per an established 45 code.

It will be observed that in my apparatus means are provided for playing upon the targets in contradistinction to bringing the targets, as in previous constructions, in regular 50 succession.

Having described my invention, what I claim as new, and desire to secure by Letters Patent, is—

1. A projecting apparatus comprising a case 55 provided with a lens, means for producing a strong light within the case, a series of independently-movable targets and a pattern mechanism adapted to throw said targets into position between the source of light and the lens in the order predetermined by said mechanism.

2. In a projecting apparatus, a case provided with a lens and a light, a series of independently-movable targets each being provided with an arm, a movable flexible pat-

tern-surface upon which the arms of said levers are adapted to rest to maintain the targets in inoperative position, said flexible pattern-surface being provided with perforations of varying lengths, the ends of said levers being adapted to enter the perforations in the 65 flexible pattern-surface to permit any one of said targets to drop into operative position between the lens and light.

3. A projecting apparatus comprising a case having an opening, means for producing a 75 strong light within the case, a series of targets each consisting of a lever having an arm carrying a character, and a trip-arm, and means for playing upon the trip-arm independently for throwing any one of the characters as 80 desired between the case-opening and the lighting means.

4. A projecting apparatus comprising a case having an opening, means for producing a strong light within the case, a series of independently-movable targets each consisting of a lever having an arm carrying a character, and a trip-arm, means for playing upon the trip-arms for throwing any one of the characters 85 as desired between the case-opening and the 90 lighting means, and means for operating the playing means.

5. A projecting apparatus comprising a case having an opening, means for producing a strong light within the case, a series of targets 95 each consisting of a lever having an arm carrying a character, and a trip-arm, a cylinder having annular unobstructed grooves, a pattern-surface for playing upon the trip-arms adapted to support the trip-arms in inoperative position over the grooves of the cylinder, and having slots through which the trip-arms fall for throwing the levers individually into operative position with the characters between the case-opening and the lighting means, and 105 means for operating the pattern-surface.

6. A projecting apparatus comprising a case having an opening, means for producing a strong light within the case, a series of targets 110 each consisting of a lever having an arm carrying a character and a trip-arm, a cylinder having annular unobstructed grooves, a pattern-surface for playing upon the trip-arms, adapted to support the trip-arms in inoperative position, over the grooves of the cylinder and having slots of different lengths through which the trip-arms fall for throwing the levers individually into operative position with the characters between the case-opening and lighting means and for controlling the length of 115 time that the characters shall be exposed, and means for operating the pattern-surface.

7. A projecting apparatus comprising a case having an opening, means for producing a strong light within the case, a series of targets 120 each consisting of a lever having an arm carrying a character and a trip-arm, a cylinder having annular unobstructed grooves, a pattern-

surface extending through the case for playing upon the trip-arms adapted to support the trip-arms in inoperative position over the grooves of the cylinder, and having slots through which the trip-arms fall for throwing the levers individually into operative position with the characters between the case - opening and the lighting means, a pressure-roller for holding the pattern-surface to the cylinder, and means

for rotating the cylinder to advance the pattern-surface.

In testimony whereof I have signed my name to this specification in the presence of two subscribing witnesses.

MORRIS MARTIN.
